ROLLOVER PROTECTIVE CAB FOR TRACTOR

John D. Wait, Jr., Dunlap, Max E. Butterfield, Peoria,
Richard Van Rossem, Canton, and Arthur E. Olt, Jr.,
Pekin, Ill., assignors to Caterpillar Tractor Co., Peoria,
Ill.

Filed Aug. 16, 1974, Ser. No. 498,040

Term of patent 14 years

Int. Cl. D15—03, 04

U.S. Cl. D40—5

FIG-1.

FIG-2.

FIG. 3.

FIG. 4.

FIG. 5.FIG. 6.FIG. 1 is a side elevational view of a rollover protective vehicle cab for tractor embodying our new design.

FIG. 2 is a side elevational view thereof of the side opposite to that shown in FIG. 1.

FIG. 3 is a front elevational view thereof.

FIG. 4 is a rear elevational view thereof.

FIG. 5 is a top plan view thereof.

FIG. 6 is a bottom plan view thereof.

We claim:

The ornamental design for a rollover protective cab for tractor, substantially as shown.
